UNITED STATES PATENT OFFICE.

WILLIAM L. CLOUSE, OF TIFFIN, OHIO, ASSIGNOR TO THE NATIONAL MACHINERY CO., OF TIFFIN, OHIO.

GRIPPING SLIDE FOR FORGING MACHINES.

Application filed June 8, 1926. Serial No. 114,509.

This invention relates to forging machines and is designed primarily as an improvement upon machines of that type shown in various patents issued to me as, for example, Patent No. 1,399,850 of December 13, 1921 and Patent No. 1,382,625 dated June 28, 1921.

In forging machines of this type there has been used a gripping slide provided with an extension for engagement with a bearing whereby the slide has been properly guided. It has been found, however, that the extension and bearing of this slide have been so located that scale and water dropping off of the gripping dies has fallen onto the extension with the result that the scale and dirt has worked quickly into the bearings of the slide and made it extremely difficult to keep these bearings in proper condition. As the bearings become worn the gripping slide tends to sag and rock with the result that the gripping dies get out of alignment and do not produce the effective result desired.

It is an object of the present invention to provide a forging machine having a gripping slide the extension and end bearing of which, however, are so constructed and located as to remain unaffected by any deposits or dirt or scale, thereby insuring accurate working of the gripping slide and elimination of the faults heretofore present in machines of this type.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings the preferred form of the invention has been shown.

In said drawings,

Figure 1 is a plan view of a portion of a forging machine having the present improvements embodied therein.

Figure 2 is a section on line 2-2, Figure 1, the gripping slide and its operating toggle being shown in elevation.

Figure 3 is a perspective view of the gripping slide.

Referring to the figures by characters of reference 1 designates the body of the machine provided with a guideway 2 in which

the heading slide 3 is mounted for reciprocation, any suitable means such as a crank 4 and pitman 5 being used for actuating this slide. Another guideway 6 is provided within the bed or body 1 and a plunger 7 is mounted for reciprocation therein, this plunger being operated by an eccentric 8 or any other suitable means carried by the shaft 9.

The guideways 2 and 6 communicate at one end with a transverse recess 10 at one end of which is located a shoulder 11 for supporting a stationary gripping die 12. The bottom of the recess 10 is extended downwardly beneath the shoulder 11 and said recess opens through one side of the bed or body 1 as shown at 13, this end of the recess being provided with bearings 14 located laterally beyond the stationary gripping die 12 and above the level of the shoulder 11. A gripping slide 15 is mounted to reciprocate within recess 10, it being provided with bearing flanges 16 at its upper end for slidably engaging the bed or body 1. Obviously the construction of the bearings can be varied to suit the manufacturer and the user, it merely being essential that they serve to support the gripping slide in proper working position within recess 10. This gripping slide is adapted to reciprocate transversely of the bed or body 1, motion being transmitted thereto in the present instance from the plunger 7 through a pitman 17 connected to a toggle 18.

The gripping slide 15 has an extension 19 projecting from the bottom thereof and so shaped as to work freely within the lower portion of the recess 10 and under the shoulder 11. The free end portion of this extension is projected upwardly and terminates in a bearing head 20 having laterally extending flanges 21 adapted to slide upon the bearings 14. It will be noted by referring particularly to Figure 2 that the engaging bearing surfaces formed by the bearings 14 and the ribs 21 are located well above the middle portion of the extension 19.

It is to be understood of course that a gripping die 22 is to be carried by the gripping slide so as to cooperate with the die 12 in the usual way.

It is believed that the advantages resulting from the use of this improved machine will be apparent. During the operation of the machine it is customary to supply water thereto. The constant action of the gripping

dies upon the work therebetween produces scale which is washed downwardly by the water and, as before explained, has heretofore tended to work into the bearings of the gripping slide and not only interfere with the proper operation of the slide but also to produce an undesirable wear thereon which has soon resulted in disalignment of the dies. With the present structure, however, the use 10 of a drop extension 19 with elevated bearings obviates this fault. It becomes impossible for the scale or other dirt to work upwardly to the bearings 14 and, consequently, the objectionable features heretofore pointed 15 out are completely eliminated and proper alignment of the dies is maintained.

What is claimed is:

1. In a machine of the class described the combination with a bed, a heading slide, and 20 a gripping die, of a gripping slide, an extension upon the slide projecting under the gripping die, and a bearing carried by the extension, said bearing being above the level of the extension.

2. In a machine of the class described a 25 heading slide, a gripping die, a gripping slide, and bearings for the gripping slide disposed at a level above the bottom of the gripping die, said gripping die being disposed between said bearings and the gripping slide. 30

3. A machine of the class described including a gripping die, a gripping slide, an extension upon the slide adapted to work beneath the gripping die, and bearings for the gripping slide and the extension, said bearings being located above the level of an intermediate 35 portion of the extension.

4. In a machine of the class described, a gripping die, a gripping slide, an extension upon the slide having an intermediate portion 40 extending across the space between the slide and die, and bearings for the slide and extension, said bearings being disposed at a level above the top of said intermediate portion of the extension.

In testimony that I claim the foregoing as my own, I have hereto affixed my signature.

WILLIAM L. CLOUSE.
